UNITED STATES PATENT OFFICE.

RUFUS N. CHAMBERLAIN, OF CHICAGO, ILLINOIS, ASSIGNOR OF ONE-HALF TO GEORGE R. BERGER, OF CHICAGO, ILLINOIS.

LOCOMOTIVE.

1,417,498.

Specification of Letters Patent. Patented May 30, 1922.

Application filed October 11, 1920. Serial No. 416,230.

To all whom it may concern:

Be it known that I, RUFUS N. CHAMBERLAIN, a citizen of the United States of America, and a resident of Chicago, county of 5 Cook, State of Illinois, have invented certain new and useful Improvements in Locomotives, of which the following is a specification.

This invention relates to electro-motive 10 means of self-contained character, and especially to locomotives, omnibuses, trucks, tractors and the like and to such devices having primary power means to supply the electrical energy required, and also having storage means to conserve the surplus power generated.

The growing demand for electrical operation of trains as in suburban service and at 15 railway terminals, including general switching at such points, presents a vast field for improvements to be worked out by the development engineer and inventor. The electrification of railway terminals involves traction problems not met in trunk line operation, even with electric railways. This arises 20 mainly from the fact that either an overhead or ground system of electric power distribution, or any combination thereof becomes extremely complex if carried out in a 25 large terminal station, or in a switching yard. Such a complicated system is not only very expensive to construct and maintain, but is easily so disarranged as to interfere seriously with service. It is moreover 30 a grave source of danger, not only to employees at all times, but also to the traveling public in case of accident.

Attempts have been made to solve this 35 problem in various ways, but so far as I am aware all methods heretofore tried have proven weak and defective in some respect, either in point of dependable operativeness or practical efficiency. For instance an internal combustion engine alone, in order to 40 respond to the relatively infrequent maximum load which it may be called upon to move, must be of so large a size as to result in running usually at a very light load and correspondingly low efficiency, not to mention the idle time chargeable to such a device. Even when a storage battery is used 45 to serve as an auxiliary or alternative power source for switching purposes, still the engine must be of large size and has little

occasion to be run at nearly full load except 55 at times, as in moving heavy trains.

The main objects of my invention are to provide an efficient quick-acting and powerful suburban passenger and freight terminal electric locomotive which will embody the 60 following advantageous features: First, it will be storage battery driven and will be of self-contained character, having its own charging plant designed to operate practically continuously at full load and maximum 65 efficiency, regardless of fluctuations in the load handled by the locomotive as a whole; second, it will be capable of use equally well on any of the old steam railway tracks, and on new tracks and terminals, no overhead 70 trolley or catenary feeding systems being required; third, it will be adapted for use in connection with the present or usual signal systems whereby the more expensive and complicated systems such as are required 75 where overhead trolleys or third rails are used may be avoided; fourth, it will be adapted for "electrification" of steam railway terminals without the necessity of reconstructing the tracks or providing power 80 stations which alone add greatly to the cost of such improvements; and fifth, it will be at all times dependable for operation at full tractive load, for a substantial period, regardless of the type of prime mover or the 85 fuel.

Still another object is to provide such a system as herein specified, embodying a smokeless locomotive of individual unit character, depending on no other units and 90 free of possibility of interference in operation through failure of power lines, third rails, central stations, coal supply, storms, ice, or other external factors. Furthermore, it is my purpose to provide a locomotive of 95 the general character stated wherein the engine-generator set may be of far less power capacity than may often be required of the motors.

An illustrative embodiment of this invention is shown in the accompanying drawings, in which—

Fig. 1 is a plan of the locomotive, part of the structure being in the section on the line 1—1 of Fig. 2, and one end being broken away.

Fig. 2 is an end elevation of the locomotive.

Fig. 3 is a section at line 3—3 on Fig. 1.

Fig. 4 is a side elevation of the locomotive except that one end is broken away.

Fig. 5 is an illustrative chart showing both a typical load curve and a normal battery charging curve for a one-day period of twenty-two hours.

Figures 6 and 7 show diagrammatically the electrical circuits involved.

10 In the construction shown in the drawings the locomotive as a whole comprises mainly a frame 1, supported on a pair of trucks 2, a direct connected prime mover 3 and electric generator 4 mounted centrally on said 15 frame and housed within the cab 5, storage batteries 6 located on both ends of said frame adjacent to said cab, one or more electric motors 7 mounted on said trucks, fuel reservoirs 8 and controllers 9. Auxiliary apparatus is 20 also provided at 10. The cab 5 is provided with a door 11 and windows 12. The internal combustion engine 3 is connected to the dynamo 4 by means of a flexible coupling 13.

The prime mover 3 is preferably an internal 25 combustion engine arranged in alignment with the generator 4, the shafts 14 and 15 being coturnably connected and disposed lengthwise of the locomotive frame 1. The batteries 6 are enclosed in protective housings 16 which are constructed for ready access to the several cells. The latter may be cut out, interchanged and renewed from time to time, as will be understood, without rendering the locomotive inoperative for any 30 considerable period. Coupling means 17 are provided at the ends of frame 1.

A preferred embodiment of my invention constructed according to a design which I consider most practical for general use, comprises 40 a locomotive frame about forty feet long and nine feet wide, and having a height at the center where the cab is located of about twelve feet. The weight of such a locomotive complete and ready for use is approximately 45 two hundred thousand pounds. I prefer a battery equipment of one hundred and twenty cells with a total power capacity of about 2400 H. P. and capable of storing about 2000 H. P. hours of energy, the gross 50 weight of the battery being about one hundred and twenty thousand pounds.

Although any one of several different types of engines might be used, I prefer an internal combustion engine of approximately 55 125 H. P. capacity. The cost of operating such an engine with oil fuel is about one cent to one and one-half cents per H. P. hour including fuel, labor and maintenance when running from three-quarters to full 60 load for twenty hours each day, such operating cost varying with varying cost of labor and fuel.

The generator to be used with said engine should have a capacity of about three hundred and fifty amperes at two hundred and fifty

volts, ranging to about three hundred amperes at three hundred volts. The series field winding may be connected in either compound or differential with respect to the shunt field, or the generator may be built with a pronounced drooping voltage characteristic as the ampere load increases and vice versa. Such machines are well known and need not be described in detail. Means may be provided whereby the attendant may alter the amount of current through the series winding if such is used. The above-mentioned type of generator is adapted to give a substantially constant wattage when operated with a suitably connected battery of proper size. This feature provides the advantage of the battery being adapted to constitute a substantially constant load on the engine which may therefore be run continuously at substantially full load. The constancy of the load on the engine may be governed by the cutting in and out of the shunts on the series winding of the generator or by other suitable devices.

Four 150 to 200 H. P. motors are provided, one for each of the four axles, said motors being preferably geared to the axles or they may be directly connected thereto when preferred, as will be understood.

The controllers may serve to place all fields in series and armatures in series for minimum power up to all fields in multiple and armatures in multiple for maximum power, and as many intermediate control combinations of fields and armatures as may be deemed advisable; with the batteries in series or in multiple units, as the operating conditions require. One arrangement of circuits is shown in Figures 6 and 7, which illustrate the use of two motors. The same 105 arrangement may apply to four or more motors.

An ampere hour meter, located in the motorman's cab, and easily visible, will always show the motorman the power which has been taken from the batteries. Besides the ampere hour meter, there will be an equally visible voltmeter, which will also indicate the condition of the battery capacity available, and so be a check on the ampere hour 115 meter. Other standard instruments and overload switches would also be conveniently located in the motorman's cab or under his control.

In Figures 6 and 7, I have illustrated one 120 arrangement of controller, Figure 6 showing a development of the controller and Figure 7 showing diagrammatically the different connections at the corresponding points of the controller, the positions *a b c d e* in 125 Figure 6 producing the connections represented by the corresponding letters in Figure 7. In these figures, the motors are represented by the letters A and B and the batteries by the letters C and D.

From these two figures it will be noted that the motors are connected in series with the two batteries in multiple. The next arrangement is with the fields in series, the 5 armatures in multiple and the batteries in multiple. The next arrangement is with the motors in series and the batteries in series. The next arrangement is with the motor fields in series, the motor armatures in multiple and the batteries in series. The fifth 10 and last arrangement is with the fields in multiple, the armatures in multiple, the batteries in series.

It is well understood that any other suitable arrangement of controller contacts may be made to produce any other desired combinations to suit particular requirements, the object of Figures 6 and 7 being merely to show one arrangement of the motors and the controller, and it is believed that the circuits 20 will be apparent from the figures shown.

This system of storage battery locomotive is based on a battery of sufficient capacity to carry maximum momentary loads up to 2400 25 H. P., and to run the engine and generator at approximately a constant load of about 100 to 125 H. P., or any suitable horse power that will keep the locomotive in service and usually leave the battery substantially 30 charged at the end of the day's work; the service, of course, being intermittent, such as occurs in suburban, passenger terminals, or freight yard service. For example, assume that the average H. P. load for 22 35 hours operation out of 24 hours, would be 100 H. P. or a total of 2200 H. P. hours. Then the engine power plant running with an output of 105 H. P. for 22 hours, would put into the battery approximately 2310 40 H. P., or 5% over the requirements of the day. The locomotive motors, however, during the day may have drawn at times peak loads of 2,000 H. P., but as the locomotive load would often be only 250 H. P., or less, 45 and at other times be zero, the average might not exceed 100 to 125 H. P. Should the ampere hour meter show the battery capacity to be below the predetermined capacity, for instance 75%, then by an adjustment of the switches controlling the shunts 50 on the series coils, the generator may be made to charge the batteries at a higher rate, and vice versa.

The cost of operation of the storage battery 55 locomotive will be at a minimum, as internal combustion engines are among the most economical power producers; also the power is produced at the point of requirement occasioning no loss in transmission. The engine running at three-quarters to full 60 load all the time not only gives maximum efficiency in fuel consumption, but minimum depreciation and maintenance in its wearing parts.

Reliability of operation is assured, as the 65 battery capacity is alone capable of giving in most cases a normal day's service, so that repairs to the engine or generator can be done at night, or, where repairs are not worth while, new parts can replace the 70 broken ones.

Worn-out batteries can be replaced in an hour, if the unit types are used. As a cell 75 wears out it can be lifted out and a good one dropped in place. A group of cells 80 working together do not wear out at the same time; hence in the course of the life 85 of the battery, only one or two at a time would ordinarily require replacing.

Since all the power generating units are 80 operated at continuously steady load, (no over-load) maximum life will be secured. The only unit or members that might be 85 overloaded are the motors, and as they are always built to stand overloads, no unusual depreciation can occur. The voltage is 90 kept normal at all times, thus never putting the armatures of the motors to any unusual strain, as is the case in other electric motor-cars, fed from trolley or third rail systems, 95 where a large drop in voltage often occurs.

Since this system of storage battery electric locomotive is an individual unit system, depending on no other units, the possibility of interference in operation is nil, for 95 there are no power lines or third rails to fail from breaking down or being covered by ice, and there can be no power station failure.

The power of storage battery locomotives 100 is exceptionally great. Their tractive effort, owing to the weight of the batteries over the drivers, is a maximum and the amount of power available is extreme. A battery can discharge at twenty times above 105 its normal rate, the limit being the carrying capacity of the motors and conductors. The battery suggested for the present design above referred to consists of 120 cells, having a discharge capacity of 16 H. P. each, 110 or a total of about 2000 H. P. Tests of that capacity have been made and continued for over 15 minutes.

Not only is the efficiency of the internal combustion engine charging plant among 115 the highest known, but the efficiency of the operation of the locomotive is exceptionally high. The voltage is always high and comparatively steady. Owing to the proximity of the batteries, the motors should 120 operate at their best efficiency. The batteries being kept fairly charged through charging from the internal combustion engine generator plant, operate at a high efficiency. The principal inefficiency of a battery 125 is due to the low voltage at the last part of a discharge and the high voltage at the end of a charge. Both these losses are largely eliminated through the large capacity of the battery not requiring complete 130

discharge to give required locomotive service except in case of breakdown of engine or generator. In fact, except for a breakdown of the engine power charging plant, 5 the battery will not ordinarily discharge over 50% of its capacity, and with such a reserve capacity, a nine-tenths charge will be all that is needed, except once a week, when a fairly full charge should be given, 10 and once in two weeks an overcharge until gravity reaches a maximum.

The above described storage battery locomotive is exceptionally responsive, since almost unlimited power for starting is available. 15 As mentioned elsewhere, 2000 H. P. is available from the battery for approximately fifteen minutes.

As an aid to the braking power of the locomotive, a system of control can be applied by which power may be turned back 20 into the batteries by making the motors act as generators.

Since all factors of the storage battery locomotive, except the storage battery, are 25 well understood and their long life appreciated, it is only necessary to state that storage battery experimenting has long shown that a battery operating under the above conditions will show not only high 30 efficiency but long life—a life of from five to seven years with suitably designed and constructed batteries.

The above suggested size of locomotive is considered a fair average for modern 35 service conditions. A larger or smaller size, of course, can be designed and built to give the same advantages. Passenger, self-propelled vehicles or cars can be readily built by using the above storage battery locomotive idea as a basis for the chassis, and building on top a suitable passenger coach with 40 a motorman's compartment at one end, or at each end; the conductor to attend to the simple operation of the engine in addition 45 to his duties as conductor. The motorman usually being more experienced can take care of the starting and adjusting of the power plant at the beginning of each day's service.

50 Although but one specific embodiment of this invention is herein shown and described it is to be understood that numerous details of the construction shown may be altered or omitted without departing 55 from the spirit of the invention as defined by the appended claims. Furthermore it is to be understood that the invention is not limited to locomotives in any strict sense; but may be largely used to advantage in 60 other forms of motor vehicles including trucks and the like.

I claim:

1. In a motor vehicle having traction

wheels, a motor for driving said wheels and adapted to take excessive load for short duration, a storage battery adapted to be connected to said motor, a charging generator for said battery supplying power thereto substantially continuously and at approximately normal full load of the generator and 65 approximately the average load on said battery, substantially as described.

2. A motor vehicle, comprising a vehicle, a storage battery carried thereby and constituting the source of driving power, an 75 electric motor connected to said battery and to the driving mechanism of the vehicle, said battery and motor being adapted to deliver excessive load for short duration, and a charging generator connected with the battery and delivering a substantially constant relatively small continuous rate of power to 80 said battery, substantially as described.

3. A motor vehicle having traction wheels and adapted for a service involving normal 85 loads and relatively large overloads, an electric motor connected to the traction wheels, a storage battery as a source of driving power and adapted to deliver relatively large overloads for short duration, means connecting said battery to said motor, and a relatively small generator for continuously charging said battery at a small rate, substantially as described.

4. A locomotive having a power equipment comprising in combination a storage battery as the driving source, and adapted to give high overload for short duration, a motor operatively connected to one of the traction wheels and connected to receive 100 power from said battery, a generator for continuously charging said battery and of insufficient power to deliver said overloads, and an engine to drive said generator, said engine and generator acting normally at substantially their full load, substantially as described.

5. A motor vehicle comprising a driving motor, a storage battery for supplying energy to said motor, a prime source of power 110 for charging said battery and having a normal load which is considerably less than that of the storage battery, substantially as described.

6. A motor vehicle comprising a single 115 unit vehicle, a motor for driving the same, a storage battery carried by said vehicle for supplying said motor, a generator operating at full load for continuously charging said battery at a rate approximately equal to the 120 average load on said battery, an engine for operating said generator, said battery having a capacity many times the full load of said generator, substantially as described.

Signed at Chicago this 7 day of Oct., 1920. 125

RUFUS N. CHAMBERLAIN.
